[57] CLAIM

The ornamental design for a computer unit, as shown and described.

DESCRIPTION

FIG. 1 is a perspective view of a computer unit showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a right side elevational view thereof, which is symmetrical to a left side view not shown herein; and,

FIG. 7 is an enlarged view of the speaker pattern shown separately for clarity of illustration only.

1 Claim, 5 Drawing Sheets
